US0D1108871S

(12) **United States Design Patent** (10) **Patent No.:** **US D1,108,871 S**
(45) **Date of Patent:** **** Jan. 13, 2026**

(54) **INTEGRATED OVEN**

(71) Applicant: **Zhejiang Aotin Electric Appliance Co., Ltd**, Shengzhou (CN)

(72) Inventors: **Wenyong Xiong**, Foshan (CN); **Honghui Shen**, Foshan (CN); **Hongkui Mao**, Foshan (CN)

(73) Assignee: **Zhejiang Aotin Electric Appliance Co., Ltd**, Shengzhou (CN)

(**) Term: **15 Years**

(21) Appl. No.: **29/956,969**

(22) Filed: **Aug. 9, 2024**

(51) **LOC (15) Cl.** **07-02**

(52) **U.S. Cl.** USPC **D7/340**; D7/339

(57) **CLAIM**

The ornamental design for an integrated oven, as shown and described.

DESCRIPTION

FIG. 1 is a perspective view of our new design, showing an integrated oven;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The line shading in FIGS. 1-8 represents contour and not surface ornamentation.

The broken lines shown in the figures illustrate environmental or other features that form no part of the claimed design.

1 Claim, 8 Drawing Sheets
